W. A. JENNINGS.
SUSPENSION THRUST RESISTING ATTACHMENT FOR PRESSES.
APPLICATION FILED MAR. 22, 1921.

1,417,997.

Patented May 30, 1922.

UNITED STATES PATENT OFFICE.

WILLIAM A. JENNINGS, OF RAYTOWN, MISSOURI.

SUSPENSION THRUST-RESISTING ATTACHMENT FOR PRESSES.

1,417,997.

Specification of Letters Patent. Patented May 30, 1922.

Application filed March 22, 1921. Serial No. 454,523.

To all whom it may concern:

Be it known that I, WILLIAM A. JENNINGS, citizen of the United States, and resident of Raytown, county of Jackson, State of Missouri, have invented a certain new and useful Improvement in Suspension Thrust-Resisting Attachments for Presses, of which the following is a complete specification.

This invention relates to suspension thrust 10 resisting attachments for presses, and more especially to attachments for presses of that class for use in placing in position and removing from position pinion gears and collars from shafts.

One of the objects of the invention is to produce a device of this character whereby the ultimate application of pressure will be to apply a tensile strain on the device of the invention and not a thrusting strain on 20 the shaft worked on, as is true with all devices of this character with which I am familiar.

A still further object is to produce a device of this character whereby provision may 25 be made for accommodating shafts provided with reduced extensions at their ends.

Another object is to produce a device of this character which will accommodate shafts of any length and reasonable diameter.

Another object is to provide means whereby the primary application of pressure will always be applied directly to the pinion or collar to be placed in position, and in which the shaft is supported throughout its 35 length against springing or bending movement.

A still further object is to produce a device of this character of simple, strong, durable, efficient and inexpensive construction; 40 and in order that it may be fully understood, reference is to be had to the accompanying drawing, in which:—

Figure 1 is a vertical section of parts conventional in any press and also shows the 45 attachment in operative relation thereto.

Figure 2 is a perspective view of the thrust resisting device of the invention, partly broken away to more clearly illustrate the same.

Figure 3 is a section similar to that of Figure 1, but illustrates the positioning of a collar on a shaft formed with a reduced extension at its lower end.

Figure 4 is a vertical section of the final 50 stage of placing a collar on a shaft of

smaller diameter than that of the previous device.

Figure 5 is a view of one stage of the removal operation of a collar from a shaft.

In the said drawing, where like reference 60 characters identify corresponding parts in all of the figures, 1 represents a suitable support constituting a part of any conventional type of press provided with an opening 2 for a purpose which will hereinafter appear. 3 is the power applying shaft of a press of the character mentioned formed, by preference, at its lower end with a reduced extension 4 for a purpose which will hereinafter appear and threaded through a 70 power applying gear wheel 5 mounted between supports 6 and adapted to be rotated by any suitable power for the purpose of causing the power applying shaft to move downwardly or upwardly according to the 75 direction of rotation of the gear wheel.

The device of the invention consists of a tubular thrust suspension device 7, provided with a closure 8 at its lower end which is provided with a perforation 9 for a purpose which will hereinafter appear. The internal diameter of member 7 will be sufficient to accommodate shafts of the greatest diameter ordinarily worked upon in a press of the character mentioned, and is equipped at 80 its upper end with a head or collar 8a, threaded or otherwise secured to member 7, formed with a shoulder 9a which is adapted to rest on the face of the support 1, and member 7 will be suspended in such position by 85 its head, it being understood that it may be made of any length found desirable to accommodate the longest shaft ordinarily worked upon, as an opening may be made in the floor or in the ground to accommodate 90 a thrust device of unusual length.

The operation of the device is as follows: For instance, it is found desirable to place a pinion on shaft 10 at a point either flush with the face of head 8 or at a point above 100 such plane (see Figure 1). The shaft 10, in this instance, being of substantially the same diameter as the tube 7, will be efficiently supported by such tube against any tendency it may have to be sprung out of line, but as such shaft is not of sufficient length to find abutment on closure 8, a spacing device 11 is inserted in the tube against which said shaft will abut as shown. In Figure 3, shaft 10 is formed at its lower end 110

with a reduced extension 12, and in order to accommodate said extension so that the pressure shall not fall thereon, a hollow spacing device 11 is supplied, which will receive the 5 reduced extension and the pressure will be applied on the shoulder formed on the shaft. In Figure 4, the shaft 10, is of smaller diameter than the tube 7, and is, therefore, supplied not only with a solid spacing device 11, but is snugly fitted in a tubular sheath 14 of substantially the same internal diameter as the shaft and external diameter as said member 7 in order to support said shaft against any tendency it may have to 15 be forced out of line by the application of pressure.

Referring now to Figure 1, pinion 15 (in Figures 3 and 4, collars 16), is forced onto the shaft by downward pressure applied by 20 shaft 3 on a spacing sleeve 17 fitted over the reduced end 4, said sleeve being of substantially the same internal diameter as the shaft 10, and coming into abutment with one face of the pinion 15 (or collars 16), and when 25 pressure is applied will force the pinion down upon said shaft as will be readily understood.

Referring now to Figure 5, it will be seen that when it is necessary to force a pinion 30 or collar 16 from position on a shaft, the shaft is inserted in member 7, said member being of greater length than the shaft, and therefore, leaving a space for the downward movement of the shaft when pressure 35 is applied at its upper end by the reduced extension 4 of shaft 3, thus forcing the collar 16 into abutment with head 8^a and forcing the shaft downward through the collar.

In practice, it will be understood that 40 member 7 will be made of any suitable diameter and length, and that when it is desired to lessen the length thereof, the necessary spacing devices 11 may be inserted, although this shortening of the length of 45 member 7 may be accomplished by a number of different means. It will also be understood that there will be a series of spacing devices 11, and sleeves 14 and 17 of varying dimensions so that shafts of varying lengths, 50 diameters, and with and without reduced end portions may be operated upon with but one thrust suspension device, it being understood in this connection that the ultimate internal diameter of member 7 must be of 55 substantially the same diameter as the shaft being operated upon in order to prevent buckling or bending of such shaft.

The opening 9 in closure 8 is supplied, in order that a wire or other instrument may 60 be used for forcing a shaft or sleeve out of member 7, should such parts have a tendency to become wedged therein.

Figure 6 illustrates a modification of the 65 means for shortening the depth of the member 7 in order to accommodate shafts of

various lengths. In this construction the closure 8 is provided with a threaded opening 9 engaged by a threaded operating shaft 18, equipped at its upper end with a false bottom 19 and at its lower end and exterior 70 to member 7 with an operating handle 20 threaded to shaft 18 or secured in any other suitable manner. The operation of this modification will be readily understood as the false bottom 19 will be advanced or 75 receded in member 7 according to the length of the shaft to be operated upon, it being understood that with the construction just described, there will be no necessity for a series of members 11 to accommodate 80 shafts of different length as hereinabove referred to.

From the above description it will be apparent that I have produced a device of the character set forth which possesses all of 85 the features of advantage pointed out as desirable, and while I have described and claimed the preferred embodiment of the same, I reserve the right to make all changes properly falling within the spirit 90 and scope of the appended claims.

I claim:

1. In a device of the character described, a tubular member adapted to receive a shaft and provided with a closure for engagement 95 by the enclosed end of the shaft, and means for supporting said member so that it shall be subjected to tensile strain by pressure imposed by said shaft on said closure.

2. In a device of the character described, 100 a tubular member open at one end and adapted to receive a shaft, a false bottom for varying the distance between said open end and the bottom thereof, and means for supporting said member so that it shall be 105 subjected to tensile strain by pressure imposed by the shaft on said first-named means.

3. In a device of the character described, a tubular member open at one end and 110 adapted to receive a shaft, a closure at the other end of said member, a device forming a false bottom adapted for insertion in said member to vary the distance between the open end of the member and the bottom 115 thereof, and means for supporting said member so that it shall be subjected to tensile strain by pressure imposed by the shaft on said first-named device.

4. In a device of the character described, 120 a tubular member adapted to receive a shaft, a closure at one end of said member, a device adapted for insertion in said member to vary the diameter thereof, and means for supporting said member so that it shall 125 be subjected to tensile strain by pressure imposed by the shaft on said closure.

5. In a device of the character described, a tubular member open at one end and adapted to receive a shaft, a closure at the 130

- other end of said member, a device forming a false bottom adapted to abut said closure and vary the distance between the open end of the member and the bottom thereof, 5 a second device adapted for insertion in said member to vary the diameter thereof, and means for supporting said member so that it shall be subjected to tensile strain by pressure imposed by the shaft on said first- 10 named device.
6. In a device of the character described, a tubular member open at one end and adapted to receive a shaft, a false bottom having threaded relation with said tubular 15 member against which said shaft is adapted to abut, and means for supporting said member so that it shall be subjected to a tensile strain by pressure applied by said shaft on said threaded means.
- 10 7. In a device of the character described, a tubular member adapted to receive a
- shaft, a closure at one end of said member, a false bottom for said member, means exterior to the member for adjusting said false bottom, and means for supporting said 25 member so that it shall be subjected to a tensile strain by pressure applied by said shaft on said threaded means.
8. In a device of the character described, a tubular member adapted to receive a 30 shaft, a closure provided with a threaded opening at one end of said member, a false bottom in said member, an operating shaft secured to said false bottom and having threaded engagement with said closure, and 35 means for supporting said member so that it shall be subjected to a tensile strain by pressure applied by said shaft on said threaded means.

In witness whereof I hereunto affix my 40
signature.

WILLIAM A. JENNINGS.
